UNITED STATES PATENT OFFICE.

HOWARD W. COTTON, OF NEW YORK, N. Y., ASSIGNOR OF ONE-HALF TO SILAS H. POMEROY, OF NEW YORK, N. Y., AND ONE-HALF TO PETER C. LENZ, OF BROOKLYN, NEW YORK.

FUSIBLE LINK.

1,092,562.

Specification of Letters Patent.

Patented Apr. 7, 1914.

Application filed November 21, 1912. Serial No. 732,790.

To all whom it may concern:

Be it known that I, HOWARD W. COTTON, a citizen of the United States, residing in the borough of Brooklyn, city and State of New York, have invented certain new and useful Improvements in Fusible Links, of which the following is a full and clear specification.

My invention relates in general to fusible links and particularly to the kind employed in holding fire doors, windows and other closures in desired positions and automatically releasing the same in the presence of high temperatures.

The object of this invention is to construct a fusible link in such manner that the members comprising the same, will, under normal conditions, safely carry the load placed upon them and automatically and positively separate when subjected to high temperatures. This is accomplished by providing each link member with a suitable opening disposed in such manner that said openings will register, when the members are placed upon each other. Within these openings is placed a holding member around which is placed the fusible element binding the link members and holding member together to form a common link.

The fusible links now used for the purposes above described are not satisfactory owing to their uncertainty in properly carrying the load placed upon them. Openings have heretofore been made in the link members to permit the fusible element to more securely bind said link members together, but even this does not remove the danger of separation caused by the strain of the load on said link.

To accomplish the object above set forth and obtain a device that will meet the requirement demanded, I have devised and constructed a fusible link hereinafter fully described in detail and the features of merit and novelty pointed out in the claims.

In the accompanying drawings Figure 1 is a face view of the two link members and the holding member bound together by the fusible element. Fig. 2 is an edge view of the same. Fig. 3 is a central section on the line 3—3 shown in Fig. 1. Fig. 4 is a view of one of the link members.

Referring to the drawings the preferred embodiment of my invention is disclosed and consists essentially of two round end links 1

and 2. These links are made of some non-corrosive material, such as brass or the like, and are broad, flat and thin with their edges reinforced or turned over at right angles to the body portion for the purpose of adding strength to the link as shown at 3 and 4. 55 The ends 1^a and 2^a are rounded and have holes or eyes 5 and 6, therethrough in which are fastened chains 9, wires or other suitable means for holding the windows, doors or closures in desired positions. Piercing the 60 body of the links are openings 7 and 8, which, when the links are placed flatwise on each other will register in the manner shown in Fig. 3. The metal surrounding these 65 holes is turned down at right angles to the body portion as shown at 7' and 8'. Placed within these openings 7 and 8 is a holding member 10 made of any suitable non-fusible material. It will be noticed that the openings 7 and 8 are approximately of the same 70 diameter so that the holding member will engage the walls of said openings at a point where the two link members engage each other. The fusible material 15 partially surrounds the holding member and firmly binds 75 it in the position shown in Fig. 3; in order that the strain produced by the weight of the closure will be taken by the holding member 10 instead of the fusible material.

The fusible material 15 is distributed between the surfaces of the link members 1 and 2 and over the ends of the same in the manner shown. The amount of fusible material used and the manner of applying it to the links to bind the same together, is not 80 an essential feature except as to its application about the holding member 10.

It is necessary that the holding member 10 be made of such shape that it will readily and freely disengage itself from the link 85 members when the fusible material, by reason of a high temperature, causes the link members to separate. I have found that the best result is obtained by making the holding member in the form of a ball. By having the entire surface of the holding member free from flattened, broken, irregular or angular lines, it will be impossible for it to retard the separation of the link members after the fusible material yields to the high 90 temperature. It will be noticed that the edge of the opening on the face of the plate is slightly rounded which permits the possi-

bility of the holding member being retarded when the fusible material yields at its lowest point of temperature.

Of course it is understood that the relative proportions of the links, openings and holding member, can be varied to suit the conditions demanded and the work to be performed.

What I claim is:

1. A fusible link comprising a plurality of link members, provided with openings, a non-fusible holding member free from angular surfaces contained within the openings of said link members and a fusible material capable of binding said holding member within the link members.

2. A fusible link comprising a plurality of link members provided with openings, a non-fusible holding member contained within said openings but not engaging the walls thereof, and a fusible element capable of binding said holding member within said openings.

3. A fusible link comprising a plurality of link members provided with circular openings extending uniformly therethrough, a ball-shaped non-fusible holding member of

less diameter than said openings, and contained within said openings and a fusible material capable of binding said holding member within said openings.

4. A fusible link comprising a plurality of link members provided with openings extending entirely through each of said link members in uniform diameter, and a ball-shaped non-fusible holding member contained within said openings and capable when fused of passing between or through said link members.

5. A fusible link comprising a plurality of link members provided with openings extending entirely through each of said link members in uniform diameter, a ball-shaped non-fusible holding member contained within said openings, and a fusible material capable of binding said holding member within said openings, said holding member when fused adapted to pass between or through said link members.

HOWARD W. COTTON.
